DESIGN FOR A COMBINED LIGHTING FIXTURE AND ORNAMENT HOLDER

Frank I. Szalla, Chicago, Ill.

Application November 4, 1943, Serial No. 111,596

Term of patent 14 years

(Cl. D48—16)

To all whom it may concern:

Be it known that I, Frank I. Szalla, a citizen of the United States and residing in the city of Chicago, in the county of Cook and State of Illinois, have invented a new, original, and ornamental Design for a Combined Lighting Fixture and Ornament Holder, of which the following is the specification, reference being had to the accompanying drawing, forming a part thereof.

On the drawing:

Fig. 1 is a top plan view of a combined lighting fixture and ornament holder showing my new design.

Fig. 2 is a cross sectional view taken on a normally vertical plane indicated by line 2—2 of Fig. 1.

Fig. 3 is a perspective view of my combined lighting fixture and ornament holder.

I claim:

The ornamental design for a combined lighting fixture and ornament holder, substantially as shown.

FRANK I. SZALLA.
